WILLIAM W. LASKER, OF BROOKLYN, NEW YORK, ASSIGNOR TO POWERS ACCOUNTING MACHINE COMPANY, OF NEW YORK, N. Y., A CORPORATION OF DELAWARE.

TOTAL-TAKING MEANS FOR ACCOUNTING-MACHINES.

1,376,555.

Specification of Letters Patent.

Patented May 3, 1921.

Application filed February 28, 1916. Serial No. 80,793.

To all whom it may concern:

Be it known that I, WILLIAM W. LASKER, a citizen of the United States, residing in Brooklyn, in the county of Kings and State of New York, have invented certain new and useful Improvements in Total-Taking Means for Accounting-Machines, of which the following is a specification.

This invention relates to accounting machines in general, and more especially to the total-taking means of accounting machines.

Among the main objects of the present invention, it is aimed to provide an improved anchoring means for the total-taking mechanism such as used in the copending application of James Powers, Ser. No. 60,629, filed Nov. 10, 1915.

With the present invention, such anchoring means are entirely removed from the total-taking shaft, and disposed adjacent to the main driving shaft, thus freeing the machine of an encumbrance where space is in demand, and disposing such mechanism where plenty of space is at hand.

25 The invention further provides a simplified construction whereby the total-taking mechanism is positively anchored in position for taking a total and contemplating a minimum of co-acting elements.

30 The invention still further contemplates the provision of improved means for actuating the total-taking shaft into total taking position.

These and other features, capabilities and 35 advantages of the present invention will appear from the subjoined detail description of one specific embodiment thereof, illustrated in the accompanying drawings, in which—

40 Figure 1 is a side elevation of a machine equipped with the present improvement.

Fig. 2 is a fragmental side elevational view of the anchoring mechanism, partly in section, showing the relative parts in anchoring position.

Fig. 3 is a fragmental end elevational view of the mechanism illustrated in Fig. 2.

Fig. 4 is a fragmental side elevational view of the anchoring mechanism, partly in section, showing the relative parts in released position.

Fig. 5 is a plan view of the anchoring mechanism shown in Fig. 2.

Fig. 6 is an enlarged detached view of

a casting forming part of the anchoring mechanism.

In the embodiment shown, there is provided a tabulating machine having a main frame A, and a card receptacle 11 from which the cards to be analyzed are fed by means of the feed rollers 12 to the position defined by the stop plate 13 between the plates 14 and 15 where the cards are analyzed by suitable pins (not shown) which set the setting pins 16, by means of which the position of the type-carrying segments disposed in the housing 17, when actuated, may be determined. Such type-carrying segments coöperate with the accumulator wheels 18 whereby such accumulator wheels 18 accumulate the several items and then, upon the actuation of the total-taking shaft 19, such wheels 18, by the interposition of the connection 20 will be set to define the position of such type-carrying segments 75 when actuated.

The means for actuating the total-taking shaft and for anchoring the same in position, which form the main part of the present invention, will now be described. 80

Disposed below the plates 14 and 15 and in which the analyzing pins (not shown) are disposed, is the pin box 21, which is connected by suitable actuating means mounted on the shaft 22 for vertically reciprocating such pin box. In such pin box 21 is disposed the initiating pin 23 which has a collar 24 disposed above the lower plate 25 of the pin box, between which collar 24 and the lower plate 25 is strained a spring 26, by means of which the initiating pin, will normally remain in raised position. Near the upper end of the pin 23 there is provided a collar 27 of slightly less diameter than the openings 28 and 29 formed in the plates 14 and 15 respectively, such collar 27 being provided to coöperate with the openings 28 and 29 of the plates 14 and 15. The lower end of the pin 23 is provided with an elongated slot 30 through which the rod portion 31 of the reciprocating bar 32 extends. The bar 32 is pivotally mounted on the upwardly extending arm 33 of the crank lever 34 which is fulcrumed at its angle to the stub shaft 35 mounted in the bearing (not shown) secured to the main frame A. The crank lever 34 also has a laterally extending arm 36, the free end of which is provided with

a cam roller 37 to engage the cam groove 38 of the cam 39 mounted on the shaft 22. Adjacent to the cam 39 there is provided a shaft 40 secured to the main frame A on which is loosely mounted the casting 41 (Fig. 6) which has an upwardly extending arm 42 provided with a lateral stop 43 thereon to coöperate with the lateral stop 44 formed on the rearwardly extending end of the reciprocating bar 32. The casting 41 also has a laterally extending arm 45 provided with an anchoring stop 46, and a link connecting arm 47, to the free end of which is pivotally connected the link 48, the upper end of which link 48 is pivotally connected to the laterally extending arm 49 fixed on the total-taking shaft 19. Fixed to the shaft 40 is the bearing bracket 50 extending laterally and downwardly therefrom, to the free end of which is pivotally connected the latching lever 51 having a latching hook portion 52 at its upper end and a pin 53 extending laterally from its downwardly extending arm 54. The hook portion 52 is resiliently strained toward the stop 46 of the casting 41 by means of the spring 55 connected between its upwardly extending portion and the bracket 50.

The periphery of the cam 39 is provided with a cut-out lug 56 for coöperating with the pin 53 of the latching lever 51.

The operation of the arrangement is substantially as follows:—The cards to be analyzed for taking a record have no perforations in alignment with the openings 28 and 29. Stop cards are provided with perforations in alignment with the openings 28 and 29 and of sufficient size to permit the passage therethrough of the collar 24, and total-taking cards are provided, as shown, in Fig. 2, by the card C with perforations just sufficiently large to permit the passage therethrough of the upper end of the pin 23 but obstruct the upward passage of the collar 24. By this arrangement, whenever a record card is passed through the machine, the pin 23 will be obstructed in its upward movement by its upper end coming into contact with the card itself and thereby the stop 44, relative to the stop 43, will be so positioned that upon the actuation of the reciprocating bar 32, by the operation of the crank lever 34, the casting 41 will not be actuated and consequently the total-taking shaft 19 will be unaffected in its operation. On the other hand, when a stop card passes through the machine, or the card supply is exhausted and no card is disposed between the plates 14 and 15, the free passage of the collar 24 through the openings 28 and 29 will position the stop 44 below the stop 43, and again, upon the actuation of the bar 32, by the operation of the crank lever 34, the casting 41 will remain idle.

65 However, when a total-taking card is

passed through the machine and the upward movement of the initiating pin 23 is obstructed by its collar 24 coming into contact with the total-taking card, the stop 44 will be disposed in the path of movement of the stop 43 so that, upon the actuation of the reciprocating bar 32 by the crank-lever 34, the casting 41 will be rocked thereby rocking its lower arm so that its stop 46 will be snapped by the portion 52 and furthermore rocking the total-taking shaft 19 by the connection of the lever 47, link 48, and lever 49. This rocking of the shaft 19 will position the accumulator wheels 18 by the connection 20 to set the type-carrying segments for taking a total. The co-action of the latch 51 with the stop 46 will anchor the total-taking shaft 19 in total-taking position until the lug 56 strikes the pin 53 thereby releasing the hook portion 52 from the stop 46, and permitting the total-taking shaft to be returned to initial position by the springs 57, which return of the shaft 19 will also restore the casting 41 to idle position.

It is obvious that various changes and modifications may be made to the details of construction without departing from the general spirit or scope of the present invention.

I claim:

1. In an accounting machine the combination of an accumulating apparatus; total-taking mechanism adapted when held set to adapt said apparatus for taking totals; card operated means for automatically setting said mechanism and anchoring means for holding said mechanism and adapted for releasing the latter after said apparatus has taken the total.

2. In an accounting machine the combination of an accumulating apparatus normally operative for accumulating; total-taking mechanism adapted when held set to adapt said apparatus for taking totals and to be inoperative for accumulating; setting means operatively connected to the total-taking mechanism and adapted when shifted to set the latter; card operated means for automatically shifting the setting means; and anchoring means for holding said setting means shifted, and adapted for releasing the shiftable means after said apparatus has taken the total.

3. In an accounting machine the combination of an accumulating apparatus normally operative for accumulating; total-taking mechanism adapted when held set to adapt said apparatus for taking totals and to be inoperative for accumulating; setting means operatively connected to the total-taking mechanism and adapted when shifted to set the latter; card operated means for automatically shifting the setting means; and anchoring means for holding said setting means shifted, and adapted for releasing

95

100

110

115

120

125

130

the shiftable means after said apparatus has taken the total.

4. In an accounting machine the combination of an accumulating apparatus normally operative for accumulating; total-taking mechanism adapted when held set to adapt said apparatus for taking totals and to be inoperative for accumulating; setting means operatively connected to the total-taking mechanism and adapted when shifted to set the latter; anchoring means for holding said setting means shifted; and a unitary means for shifting the setting means and releasing the anchoring means.

15 5. In an accounting machine the combination of an accumulating apparatus; total-taking mechanism adapted when held set to adapt said apparatus for taking totals; setting means operatively connected to the total-taking mechanism and adapted when shifted to set the latter; a continuously rotary driving cam; card operated means adapted to be interposed between said rotary cam and said setting means for shifting the setting means; and anchoring means for holding said setting means shifted, and operated by said rotary cam for releasing the shiftable means.

6. In an accounting machine the combination of an accumulating apparatus normally operative for accumulating; total-taking mechanism adapted when held set to adapt said apparatus for taking totals and to be inoperative for accumulating; setting means operatively connected to the total-taking mechanism and adapted when shifted to set the latter; a rotary driving means for shifting the setting means; and anchoring means for holding said setting means shifted, and operated by said rotary means for releasing the shiftable means.

7. In an accounting machine the combination of an accumulating apparatus normally operative for accumulating; total-taking mechanism adapted when held set to adapt said apparatus for taking totals and to be inoperative for accumulating; setting means operatively connected to the total-taking mechanism and adapted when shifted to set the latter; a rotary driving cam-means moving without reversal; card operated means adapted to be interposed between said rotary means and said setting means for shifting the setting means; and anchoring means for positively holding said setting means shifted, and adapted to be operated by said rotary means for releasing the shiftable means after said apparatus has had time to take a total.

60 8. In an accounting machine, the combination of an accumulating apparatus; a total taking mechanism adapted when set to adapt said apparatus to take a total; a movable means operatively connected to said total-taking mechanism for setting the latter; and

a latch for retaining said movable means in set position.

9. In an accounting machine, the combination of an accumulating apparatus; a total taking mechanism adapted when set to adapt 70 said apparatus to take a total; a movable means operatively connected to said total-taking mechanism for setting the latter; a latch for retaining said movable means in set position; and automatic means for releasing 75 said latch.

10. In an accounting machine, the combination of an accumulating apparatus; a total taking mechanism adapted when set to adapt 80 said apparatus to take a total; a movable means operatively connected to said total-taking mechanism for setting the latter; a latch for retaining said movable means in set position; and automatic means for setting 85 said movable means and releasing said latch.

11. In an accounting machine, the combination of an accumulating apparatus; a total taking mechanism adapted when set to adapt said apparatus to take a total; a movable means operatively connected to said total 90 taking mechanism for setting the latter; a latch for retaining said movable means in set position; and cam means for releasing said latch.

12. In an accounting machine, the combination of an accumulating apparatus; a total taking mechanism adapted when set to adapt said apparatus to take a total; a movable means operatively connected to said total taking mechanism for setting the latter; a 100 latch for retaining said movable means in set position; and cam means for setting said movable means and releasing said latch.

13. In an accounting machine, the combination of an accumulating apparatus; a total taking mechanism adapted when set to adapt said apparatus to take a total; a cam; a bar reciprocated by said cam having a lateral stop; card actuated means for moving said bar to total taking position; a pivotally 110 mounted member provided with an arm, an anchor-stop, and a lateral stop adapted to engage said first-named stop; a link connecting said mechanism with said arm; a latching lever having a hook adapted to 115 catch said anchor-stop; and a cut-out lug on said cam and adapted to engage and rock said latching lever.

14. In an accounting machine, the combination of an accumulating apparatus; a total 120 taking mechanism adapted when set to adapt said apparatus to take a total; a cam; a bar reciprocated by said cam; total taking card actuated means adapted to move said bar to total taking position; a movable member 125 provided with a latching stop, and a total taking stop adapted to coöperate with said bar when in said position; an operative connection between the total taking mechanism and said movable member for setting the 130

total taking stop when said movable member is actuated; a latch adapted to engage said latching stop and hold said member in actuated position; and means carried by said cam 5 for releasing the latch.

15. In an accounting machine, the combination of an accumulating apparatus; a total taking mechanism adapted when set to adapt said apparatus to take a total and provided 10 with a total taking shaft provided with a total taking crank; a grooved cam; a crank lever having one arm engaged in said groove of the cam for rocking the lever; a reciprocating pin box; an initiating pin in said pin 15 box and adapted to assume an intermediate position on the passage of a total taking card through the pin box, and provided with a slot at its lower end; a reciprocating bar pivoted to the other arm of said crank lever and having, at one end a laterally extending stop, 20 and at the other end a rod portion extending through said slot; a fixed shaft; a casting

pivoted on said fixed shaft and having a link-connecting arm, a laterally extending arm and an upwardly extending arm; a lateral stop on the upwardly extending arm adapted to engage the stop on said bar when the bar is in mid position; a stop on the laterally extending arm; a link connecting said total taking crank with said link connecting 25 arm; a bearing bracket fixed on said fixed shaft; a latching lever pivoted on said bearing bracket and provided with a hook at its upper end adapted to engage over said stop on said laterally extending arm; a cut-out 30 lug carried on said cam; and a laterally extending pin on the lower end of the latching lever and adapted to be engaged by the cut-out lug.

WILLIAM W. LASKER.
